E. A. BURBANK

DISPLAY RACK

Filed April 15, 1922

FIG. 1.

FIG. 2.

18-8 15 FIG. 3

FIG. 4-

116

Inventor
Edward A. Burbank
by Hubert W. Jenner,
Attorney.

UNITED STATES PATENT OFFICE.

EDWARD A. BURBANK, OF BOSTON, MASSACHUSETTS.

DISPLAY RACK.

Application filed April 15, 1922. Serial No. 552,836.

To all whom it may concern:

Be it known that I, EDWARD A. BURBANK, a citizen of the United States, residing at Boston, in the county of Suffolk and State 5 of Massachusetts, have invented certain new and useful Improvements in Display Racks, of which the following is a specification.

This invention relates to racks for displaying cards, pictures, and small articles, 10 and which are journaled to revolve on vertical spindles; and it consists in the novel construction and combination of the parts hereinafter fully described and claimed.

In the drawings, Figure 1 is a side view 15 of a rack constructed according to this invention, a portion of the frame being broken away to show one top crossbar in section. Fig. 2 is sectional plan view, taken on the line 2—2 in Fig. 1. Fig. 3 is a cross-section 20 through one of the horizontal plates, taken on the line 3—3 in Fig. 2. Fig. 4 is a plan view of a frame having three side panels.

A vertical spindle 6 is provided, and it projects from any suitable base 7, which may 25 be stood on a table or counter.

The frame 8 is preferably formed of thin sheet metal bars and plates, so as to be as light as possible. The frame may have three side panels, as shown in Fig. 4, or 30 four side panels as shown in Fig. 2, or it may have any additional number of side panels. Each frame has a lower horizontal plate 9, and an upper horizontal plate 10, of thin sheet metal provided with flanges 35 12 at their edges. These plates are shaped to suit the number of side panels to be secured to them, and they are both alike, but the flanges of the upper plate project downwardly, and those of the lower plate project 40 upwardly. The side panels of the frame are secured to the flanges 12, and the frame projects vertically above the upper plate for about twice the distance between the plates. This enables a shorter spindle to be used.

45 Each horizontal plate has a hole in its middle part, and an eyelet 14 is placed in the hole and bent over so as to secure it. These eyelets are journaled on the center spindle, and the bottom eyelet rests on the base 7, so 50 that the frame can be revolved. These eyelets have flanges 14' which are secured against the plates 9 and 10, and they have convex tubular portions which bear against the spindle 6. The lower eyelet also bears 55 on the base 7. These eyelets form anti-friction bearings for the rack, and enable the

plates 9 and 10 to be made of very thin metal. The panels of the frame are all alike in size and shape, so that they can be made inexpensively in large quantities, and used 60 interchangeably in building up the frames. The side bars are relatively narrow in proportion to the length, and are soldered together at their edges to form a frame having the predetermined number of panels. 65 This construction enables racks to be made of relatively large size and light weight, and very rigid and strong, and suitable for the display of small articles (such as bags of salted nuts) which are attached to stout 70 cards which are slid in the panels of the frame.

Each side panel is formed of two vertical bars 15, a top crossbar 16, and a bottom crossbar 17. Each vertical bar 15 is hook-shaped in cross-section, and its wider part is secured against the two crossbars, so that a channel is formed at the front of the panel in which a card 18 or other similar support may be slid. One card 18 is shown in Fig. 80 3, and it may be a picture card, or it may have advertising matter on it, or it may have small articles secured to it by any suitable means. The bottom crossbar 17 is also hook-shaped in cross-section, and it forms 85 a bottom for the guide channel in which the display card is slid and supported.

The top crossbar 16 is also hook-shaped in cross-section, but its hook is bent closer to its broad part so as to form a narrow 90 bead on the inside of the frame, which stiffens the crossbar and does not obstruct the channel in which the display card is slid. The side panels of the frame are secured 95 together at the backs of their hooks by solder 20, as shown in Fig. 2, or by any other approved means.

When a large display rack is made, its sides may be formed of a plurality of panels arranged edge to edge. In the form of the 100 rack shown in Fig. 4, one of the sides of the frame is shown provided with two additional vertical bars 15' secured edge to edge and arranged at the middle part of the main panel and forming two narrow panels. A 105 display card 18' is slidable in each narrow channel, in a similar manner to the card 18.

What I claim is:

In a display rack, a skeleton frame formed of a series of similar vertical panels secured 110 edge to edge and arranged around a common axis, each panel comprising side bars, a top

bar and a bottom bar secured together in rectangular form and having an open space between them, all of said bars being hook-shaped in cross-section and the hook of the top bar being arranged to project inwardly and in the reverse direction from the hooks of the side and bottom bars which form a channel for a card, a horizontal plate secured at the bottom ends of the panels, a

horizontal plate secured to the panels intermediate of their ends, each horizontal plate being provided with a bearing at the axis of the frame, and a supporting base and axial spindle upon which the said bearings are journaled.

In testimony whereof I have affixed my signature.

EDWARD A. BURBANK.
